Application April 15, 1940, Serial No. 329,704

19 Claims. (Cl. 242—45)

The present invention relates to winding and reeling apparatus and more particularly to devices for winding material in strip or wire form onto a storage roll to which it is delivered at constant speed.

When material in strip or wire form is being wound on a drum, reel, spool, or other storage roll and such material is being delivered to the roll at a predetermined speed, the increase in diameter of the wound mass on the roll tends to cause the material to be wound faster than it is being delivered with the result that as the diameter of the wound mass increases the material being delivered to the drum or roll will be subjected to an increased tension or pulling strain.

The primary object of the present invention is to store long lengths of material by winding and rewinding under controlled conditions.

A further object is to provide improved means for controlling the operating conditions of a wire or strip working process in terms of the speed and tension of the wire or strip as it is being delivered either to or from the processing machine.

Another object is to provide a closer regulation of the speed and tension control over the regulation offered by prior art machines and particularly where the operations are continuously variable and in the same direction.

A more specific object is to provide a novel means for controlling the speed of rotation of the drum or roll by which the speed of rotation is decelerated as the diameter of the wound mass increases or vice versa so as to maintain a substantially constant tension on the material being delivered to or from the drum or roll.

The foregoing objects are attained, in brief, by providing a means for rotating the drum or roll through a variable speed transmission which has a power shaft, an output shaft and a variable speed driving connection between the shafts, together with an improved means controlled by the tension of the strip or wire being delivered to or from the drum or roll for adjusting this variable speed driving connection so as to maintain a speed of rotation of the drum which will provide at all times the desired tension on the material being delivered to or from the drum.

Other objects and features will be apparent after the specification is perused in connection with the accompanying drawings.

In the drawings:

Figure 1 is an elevational view of the improved constant tension winder;

Figure 2 is an elevational view of the driving mechanism for the winding machine, including the variable transmission for the storage roll of material;

Figure 3 is a sectional view of the motor which actuates the driving mechanism shown in Figure 2;

Figure 4 is a sectional view taken along the line 4—4 in Figure 3 showing the operation of the balancing weight and the handle control mechanism on the motor which drives the variable transmission;

Figure 5 is a plan view of the contactor forming a part of the driving mechanism;

Figure 6 is a composite view shown in exaggerated form to bring out the details of the component switch parts of the contactor shown in Figure 5 with the parts in typical corresponding positions. The various parts of this figure, labelled section B—B; section D—D; section C—C and section E—E, are views taken along sectional lines of corresponding letter in Figure 5;

Figures 7 and 8 are views similar to section D—D in Figure 6 but showing the successive positions assumed by the different parts as the actuating shaft is rotated;

Figure 9 is a circuit diagram showing the connections between the electric mains, the pilot motor and the main source of mechanical power, together with a switch mechanism for controlling the operation of the pilot motor.

An unwind roll 1 of strip material 2 upon which work is to be performed in process is mounted upon shaft 3 in stand 4. The shaft 3 may be free turning to permit strip 2 to be pulled into work performing machine 5, or may include a drag brake 6 to prevent the unwind roll from overrunning, or may be power driven to control tension in strip 2 between the unwind roll 1 and the work performing machine 5 by means of an additional driving mechanism 7, as the process requires.

The work performing machine 5 is power operated by motor 8. Where strip 2 is processed over a range of linear speeds, power is supplied over a range of operating speeds by means of the variable speed transmission 9, wherein speeds are adjusted manually by handwheel 10. For convenience, a panel 11 mounting controlling devices for driving mechanism 7 may be mounted at machine 5. In process with work performing machine 5 is a rewind roll 12 for storing strip 2 leaving machine 5. Storage roll 12 mounts on and rotates with shaft 13 carried by stand 14. Driving mechanism 7 power operates storage

roll 12 by suitable means, as sprockets 15 and 16 and chain 17, at speeds which are adjusted for the linear delivery of strip 2 from machine 5 at rates to permit the storage roll 12 to build up in diameter under a constant tension in strip 2 between machine 5 and storage roll 12. The driving mechanism 7 consists of a constant speed power source 18 connecting by suitable means, as sheaves 19 and 20 and ropes 21, to input shaft 22 of variable speed transmission 23. Output shaft 24 of variable speed transmission 23 carries sprocket 15 described above. The driving mechanism includes tension controlling means to be described further.

Input shaft 22 and output shaft 24 each mount cone discs 25 in pairs, engaging with edge active belt 26. Discs 25 are connected by thrust bearings 27 to levers 28. Levers 28 are pivoted at 29 and connected by nuts 30 to speed changing screw 31. By revolving screw 31 ratio of speeds between input shaft 22 and output shaft 24 is varied. The pilot motor 32 is equipped with brake 33 and gear head 34 and connected by coupling 35 to speed changing screw 31.

The constant speed power source 18, preferably a motor, is mounted by flanges 36 and 42 fastened to motor frame or stator 37 carried by bearings 38, preferably a self-aligning type. Bearings 38 are located by pedestals 157 and 43. Bearings 38 are concentric with but are not connected to motor shaft 39. Motor shaft 39, located by bearings 40 and carrying rotor 41, is the conventional construction. Pedestals 157 and 43 are supported upon brackets 45 carried by frame 44 of variable speed transmission 23. Adjustable stops 46 at flange 42 for engaging bumper 47 at pedestal 43 limits free rotation of stator 37 to a few degrees. The flange member 42 is secured to the stator member 37.

The screw 48 threaded through lugs 49 at 40 flange 36 carries weight 50 at one end and handwheel 51 at the other. By manually operating handwheel 51, screw 48, weight 50, and handwheel 51, may be positioned to counterbalance any predetermined reaction of stator 37. By 45 turning handwheel 51 to extend screw 48 to its extreme left position, the moments of the weights counterbalance the torque reaction of stator 37 for motor 18 full load capacity.

Rotor 41 and shaft 39 rotate on bearings 40. Stator 37 is suspended concentrically with shaft 39, but independently by bearings 38. Shaft 39 may extend in either direction through adjacent bearing 38 to carry sheave 19, but does not engage bearing 38. Link 52 is pivoted to flange 42 by pin 53. The other end of link 52 is pivoted to lever 54 by pin 55. The other end of lever 54 is fastened to operating shaft 56 of contactor 57.

With driving mechanism 7 running under load, any deviation from load setting tilts stator 37. This motion is transmitted to rotate contactor shaft 56 in one direction or the other. Contactor shaft 56 carries four sets of insulated electrical contacts shown at B-B, C-C, D-D, and E-E. Contactor frame 58 carries four sets of insulated electrical contacts, preferably of the conventional double-break type. At the inoperative, or normally open position of contactor 57, contact separation at 59 is spaced wider for sets B-B and C-C than for sets D-D and E-E, so that rotation of shaft 56 will engage contacts at E-E before C-C, or D-D before B-B. Sets B-B, C-C, and E-E are constructed so that rotation of shaft 56 in excess of the amount re-

quired to engage contacts will maintain contact engagement until shaft 56 returns to the position at which contacts engaged, in the following manner:

5 The arm 60 is keyed to shaft 56. Bar 61 is pivoted to arm 60 by pin 62. Bar 61 carries contact element 63 of sufficient length to engage the two contacts 64 and 67 carried by frame 58. With contacts disengaged, bar 61 is positioned by spring 65 and stop 66. When rotation of shaft 56 engages element 63 with contacts 64 and 67, further rotation compresses spring 65. Compression of spring 65 maintains contact engagement until reversal of rotation of shaft 56 returns to disengage contacts at the position where this engagement previously occurred.

As will be described hereinafter, contact engagement at B-B or C-C obtains continuous operation of pilot motor 32 in one or the other direction of rotation, to provide a rapidly increasing or decreasing rate of rotation of output shaft 24. The contact engagement at D-D or E-E causes repeated incremental operation of the pilot motor 32 to provide slight, gradual speed adjustments.

At a given speed of the roll shaft 13 during the windup of strip 2 at storage roll 12, assuming the proper tension in the strip as determined by the manual adjustment at handwheel 51, the further wrapping at the storage roll 12 increases its diameter and the peripheral speed of the roll, and increases the tension in strip 2 between the machine 5 and storage roll 12. In the direction the strip 2 approaches storage roll 12, shafts 13, 24, 22 and 39 rotate counterclockwise. Since the position of weight 50 no longer counterbalances the increased load on power motor 18, the stator 37 rotates clockwise, raising weight 50, and rotating shaft 56 of contactor 57 in the direction to engage contacts E-E. If the responding incremental speed adjustments are insufficient to restore the tension setting, rotation of the contactor shaft 56 will continue, and engage contacts C-C to obtain a rapid speed adjustment.

It will be observed that slight deviations in load setting recur frequently during the normal rewind of strip 2 at storage roll 12. But there may also occur unpredictable, possibly sudden changes under actual operation, for example, sticking or momentary stoppage of strip 2 through machine 5. The operation of contactor 57 provides for both the slight and the wider, and possibly more rapid deviations in tension.

The effect of the responding speed adjustments will stop further clockwise rotation of stator 37, as described heretofore. Its rotation now reverses and the stator 37 returns to the balanced position. In effect, the stator 37 has oscillated slightly from its balanced position during the period of deviation from the load setting. The speed adjustment thus obtained will become sufficient to correct the accumulated error when the rotation of stator 37 reverses and starts returning to its initial position. But the contact sets B-B, C-C, and E-E still maintain engagement and continue the speed adjustment until the return-to-balance reaches the slight deviation at which point the contacts had engaged, and now disengage.

For wider deviation within the range of the setting of contacts B-B and C-C, the effect is to shorten the interval of off-balance by increasing the amount of rapid adjustment to not only correct the error in rate but to assimilate

the accumulated amount of error. Where the driving mechanism 7 operates to control the tension of the strip or wire being wound on the storage roll 12, these slight, frequently recurring deviations are normally in the same direction because the diameter at the storage roll is continuously increasing. The effect of maintained contact at the closely spaced set E—E is avoided by providing speed adjustments slightly in excess of the instantaneous requirements to meet the quickly recurring demand for further slight adjustment. Additional beneficial action is obtained under these circumstances because a lesser amount of error accumulates, and closer control is maintained. In case the deviations are largely in the same direction during normal operation, speed decreasing adjustments to lessen tension sufficiently in excess of demand will unbalance the setting enough to lower weight 50 from its balanced position and engage contact set D—D. In practice, a decrease in thickness of strip 2 will have the same effect. It will be observed that such an error is only momentary inasmuch as the continuously increasing diameter at the storage roll 12 will shortly demand further speed decreasing adjustments. Instead of maintaining the contact at D—D, provision is made for disengagement of this contact as quickly as the speed increasing adjustments have assimilated the accumulated amount of error.

The arm 68 is keyed to the shaft 56. The link 72 is pivoted to arm 68 by the pin 74 and positioned by spring 73 against the stop 81 on arm 68. The bar 79 is pivoted to link 72 by the pin 80. The drag 76 is pivoted to link 72 by the pin 75. The frictional engagement of drag 76 is applied by spring 78 along quadrant 82 of bar 79. The counterclockwise rotation of shaft 56 swings arm 68 and link 72 and bar 79 to engage element 69 with contacts 70 and 71 carried by the frame 58 of contactor 57. Further rotation of shaft 56 continues contact engagement by frictional lift of drag 76 against quadrant 82. Reversal of rotation of shaft 56 releases contact engagement by lowering bar 79. Continued clockwise rotation of shaft 56 will cause the bar 79 to engage the stop 83 carried by contactor frame 58, and causes the drag 76 to slip along the quadrant 82 of bar 79 until the drag member strikes stop 77 on the quadrant 82. This is the mid or inoperative position of shaft 56. The contact element 69 is now reset to the closely spaced position 59 for reengagement. Clockwise rotation of the shaft 56 from mid position to engage speed decreasing contacts, compresses the spring 73. Compression of the spring 73 maintains the bar 79 and link 72 positions by engaging the stops 83 and 77. The arm 68 rotates with shaft 56 while the link 72 pivots at pin 74.

The starting switch 84 connects driving mechanism 7 to the power line by leads 85, 86, and 87 to the power motor 18, and leads 88, 89 and 90 to the panel 11. The pilot motor 32 connects with panel 11 by the leads 91, 92, and 93. Contactor 57 connects with panel 11 by the leads 94, 95, 96, and 97.

The panel 11 carries a solenoid-operated reversing switch indicated generally at 98 and a motor-operated timer indicated generally at 99. The reversing switch 98 comprises two 4-pole 70 contactors with normally open contacts and a mechanical interlock, all of conventional design. The timer 99 consists of a motor 100 with an output shaft 101 running at a suitable speed. The shaft 101 carries a multipoint cam 102. The 75

speed of the motor shaft and the number of cam points may be changed, as desired, to provide regularly spaced intervals to suit operating conditions. The follower 103 engages cam 102 and pivots on pin 104. Contact arm 105 pivots on follower 103 at pin 109. The screw 106 is threaded into arm 105. The spring 110 holds screw 106 in yielding engagement with stop 111 of follower 103. By turning the screw 106, the spacing 107 between contact 108 and arm 105 is adjusted to regulate length of contact engagement during each cam point interval. The timer motor 100 is connected to run continuously while driving mechanism 7 is operating, through the following circuit: from the switch 84 through leads 90, and 114 to motor terminal 112, and from the motor terminal 113 through lead 117 back to the switch 84.

The engagement of set E—E at contactor 57 20 obtains incremental speed adjustments at the variable speed transmission 23 through the following circuits: with the contacts engaged at E—E, one of the contactors of reversing switch 98 is operated at the instant timer 99 circuit closes, as follows: from switch 84 through leads 90, 114, 118, arm 105, contact 108, leads 97 contact 120, element 121, contact 122, lead 95 to the solenoid 126; from switch 84 through leads 89, 117 and 125 to the other side of the solenoid. 25 The plunger 128 of solenoid 126 then closes the following circuits to operate the pilot motor 32; switch 84, leads 88 and 129, contact 130, element 131, contact 132, leads 133 and 93 to pilot motor terminal 134, switch 84, leads 89 and 135, contact 136, element 137, contact 138, leads 139 and 92 to the pilot motor terminal 140, and switch 84, leads 90 and 142, contact 143, element 144, contact 145, leads 146 and 91 to the pilot motor terminal 141.

In like manner the circuit engagement for set D—D at the contactor 57 will operate the solenoid 147 for the other contactor of reversing switch 98, which, in turn, will operate the pilot motor 32. Reversal of the circuits to the pilot motor for reversing the direction of rotation is obtained by reversed interconnections 133 and 146 between the contactors of the reversing switch 98.

Once the reversing switch starts operation, the 50 switch contacts are held in engagement until the circuit is opened at the timer bar 105 and contact 108, regardless of the circuit engagements or disengagements at contactor 57. A holding circuit is established for this purpose. Referring to the circuit described above for starting the operation of solenoid 126 and moving plunger 128 to close the contacts set forth, the circuit to solenoid 126 is now as follows: from the switch 84 through leads 90, 114, 118, bar 105, contact 108, leads 158 and 148, contact 149, element 150, contact 151, and lead 152 to the solenoid 126; from the solenoid 126 through leads 125, 117, and 89 to the switch 84.

The contacts at contactor 57 might barely engage and only slightly separate. The arrangement described provides for only the initiating operation at the contactor 57. Breaking circuits at the timer 99 enables contact areas and pressures and separation to be regulated for minimum arcing and disintegrating of contact material. It prevents switch chatter and provides increments of speed adjustment in controlled definite amounts. The use of timer 99 provides these increments only at regularly spaced intervals

which are controlled for the rate of diameter build-up at the storage roll.

Where the incremental adjustments are insufficient to restore tension setting as indicated for example by rotation of contactor shaft 56 to first engage the contact set E—E and with continued rotation to next engage set C—C, the operation of pilot motor 32 now becomes continuous, since the operation of solenoid 128 of reversing switch 98 is continuous until contact disengagement of set C—C. This circuit is as follows: from switch 84 through leads 90, 114, 118, 94 contact 153, element 154, contact 155, lead 123 to the solenoid 126; from the solenoid 126 through leads 125, 117, and 89 back to the switch 84. In like manner, the operation of pilot motor 32 is continuous in the reverse direction of rotation during engagement of set B—B at contactor 57 by the continuous operation of solenoid 137 of the other contactor of reversing switch 98.

It is evident from the circuit diagram of Figure 9, that the main function of the contact set C—C and the corresponding set B—B is to short circuit the timing device 102 whereby the current to the pilot motor 32 is applied continuously, and without interruption by the timing device. When the tension on the wire or strip 2 is so unusual as to necessitate immediate and considerable adjustment in the speed of the storage roll, thus causing shaft 56 to rotate sufficiently to close the contact set C—C (or the corresponding opposite set B—B under reverse conditions) the pilot motor continues to operate until the required changes in storage roll speed have been effected. However, under normal conditions, only the contact set E—E (or the corresponding opposite set D—D) will be closed and the storage roll speed adjustments are effected intermittently through the timer 102.

It may be desirable to provide a magnetic brake, of any suitable and well-known type and indicated at 155, on the shaft of the pilot motor in order to prevent overrunning, hunting or surging. The electromagnetic element 156 of the brake may be energized from one of the phases of the electric mains through suitably positioned contacts of the switching mechanism as shown.

From the foregoing, it is evident that we have disclosed means for winding a strip of material onto a drum or spool and controlling the speed of the drum or spool so that a constant tension is maintained on the strip being wound. This is accomplished by providing a power source having a member whose position is affected by changes in the tension on the strip, and when this member changes its position it operates means which change the driving ratio of the power means operating the drum in whichever direction is necessary, i. e., faster or slower, so that constant tension is maintained. The predetermined tension on the strip is fixed in this case by adjusting the position of the weights 51 and 59 in relation to the center of the motor, as shown in Figure 3. When the tension changes for any reason, such for instance as the wire moving toward or away from the center of the spool, then if the rotary speed of the spool were constant the tension on the strip would increase as the wire moves toward the end of the spool, or decrease as it moves toward the center of the spool. These changes in tension cause the sensitive member to move, and through suitable mechanical and electrical connections decrease or increase the speed of the drum to maintain the

predetermined tension at which the control is then set to operate. While in most processes of this kind the material is fed to the spool at an approximately constant speed, these controls would operate just the same if there were variations in the feeding speed. To illustrate, if the feeding speed were increased or decreased, this would tend to reduce or increase the tension and cause the sensitive means to move, and through the various control parts change the drum speed to maintain the predetermined setting.

It will be observed that driving mechanism 7 may be applied as readily with equally satisfactory results to the unwind roll 1 in the manner described for its application to the rewind or storage roll 12. One of the two changes required for this different application would be to relocate contact set D—D in the position of set E—E, and set E—E in the position of set D—D, inasmuch as the continuous and gradual reduction in diameter of unwind roll 1 would demand frequent repeated speed increasing adjustments. The other change would be to relocate weight 59 in the position of handwheel 51 on screw 43, and handwheel 51 in the position of weight 59.

The term "driving mechanism" as applied to the mechanism 7 for operating unwind roll 1 would not be quite accurate because this mechanism now becomes a "brake mechanism," although it performs its function in the same manner described heretofore. Inasmuch as a power source 18 with constant speed characteristics is employed, power in whatever amount the operation demands, is applied to maintain rotation at the fixed speed of the power source. When the mechanism 7 is applied to the rewind roll 12 it functions as a driver by operating the roll to draw sheet 2 at rates to apply a controlled increment of tension in strip 2 between the work performing machine 5 and rewind roll 12. The machine 5 draws strip 2 from the unwind roll 1. When the mechanism 7 is applied to the unwind roll 1 free rotation of unwind roll 1 is resisted by operating unwind roll 1 at rates to impose a controlled increment of tension in strip 2 between the unwind roll 1 and work performing machine 5.

The power source 18 does not resist rotation. Where a motor is employed, its electrical connections require rotation in the direction to the delivery strip 2 from the unwind roll 1. But changing the function of the mechanism 7 changes the direction of the torque reaction at stator 37, and therefore requires reversing the location of the adjustable weight 59 and handwheel 51 as described above. The setting of the weight determines the amount of the braking effect by operating the unwind roll 1 with mechanism 7 at rates to control the tension at the predetermined value.

The power source is not limited to the use of a motor. A turbine with constant speed characteristics, coupled to the input shaft of the variable speed transmission is equally applicable. Likewise, the type of controlling devices, their construction and interconnection is only one of several equally suitable arrangements that may be employed to advantage.

While there has been shown and described the application of the driving mechanism to storage rolls in connection with any work performing machine, it is understood that the application of the invention is not limited to this particular use. Obviously, the driving mechanism may be applied to any machine or process for operating

upon work in control of some phase of the process, responsive in terms of power, speed, or tension.

It will be understood that we desire to comprehend within our invention such modifications as come within the scope of the claims and the invention.

Having thus fully described our invention, what we claim as new and desire to secure by Letters Patent is:

1. An apparatus for winding strip or wire material onto a roll and delivered thereto at an approximate constant rate, said apparatus including a variable speed transmission mechanism for rotating the roll at a rate dependent on the tension of the strip, said mechanism being actuated by a motor, said motor having a portion independent of the rotor and which is adapted to move over a distance dependent on the amount of change of tension in the strip, and means actuated by the movement of said motor portion for changing the power transmission ratio of said transmission mechanism whereby the speed of the roll is changed in accordance with the changed tension of the strip.

2. An apparatus for winding strip or wire material onto a roll and delivered thereto at an approximate constant rate, said apparatus including a variable speed transmission mechanism for rotating the roll at a rate dependent on the tension of the strip, said mechanism being actuated by a motor, the stator of which is adapted to move through an angle dependent on the amount of change of tension in the strip, and means actuated by the angular movement of said stator for changing the power transmission ratio of said transmission mechanism whereby the speed of the roll is changed in accordance with the changed tension of the strip.

3. An apparatus for winding strip or wire material onto a roll and delivered thereto at a constant rate, said apparatus including a variable speed transmission mechanism for rotating the roll at a rate dependent on the tension of the strip, said mechanism being actuated by the rotor of a motor which also includes a stator, said stator being mounted on a frame through a rotary bearing and adapted to receive rotational energy from said rotor when the tension on the strip changes from a predetermined value, and means actuated by the rotary movement of the stator on its bearing for changing the power transmission ratio of said transmission mechanism whereby the speed of the roll is changed to maintain the predetermined tension of the strip.

4. An apparatus for winding strip or wire material onto a roll and delivered thereto at an approximate constant rate, said apparatus including a variable speed transmission mechanism for rotating the roll at a rate dependent on the tension of the strip, said mechanism being actuated by the rotor of a motor which also includes a stator, said stator being mounted on a frame through a rotary bearing and adapted to receive rotational energy from said rotor when the tension on the strip exceeds a predetermined value, an adjustable counterbalancing device secured to said stator for determining the tension of the strip at which the stator will rotate, and means actuated by the rotary movement of the stator on its bearing for changing the power transmission ratio of said transmission mechanism whereby the speed of the roll is changed to maintain

the predetermined tension at which the counterbalanced stator rotates.

5. An apparatus for winding strip or wire material onto a roll and delivered thereto at an approximate constant rate, said apparatus including a variable speed transmission mechanism for rotating the roll at a rate dependent upon the tension of the strip, said mechanism being actuated by the rotor of a motor which also includes a stator, said stator being mounted on a frame through a rotary bearing and adapted to receive rotational energy from said rotor when the tension on the strip exceeds a predetermined value, means for determining the tension of the strip at which the stator will be rotated, and means actuated by the rotary movement of the stator on its bearing for changing the power transmission ratio of said transmission mechanism whereby the speed of the roll is changed to maintain the tension at which the stator rotates.

6. An apparatus for winding material in strip or wire form which is being delivered at a predetermined rate, said apparatus comprising a main frame and a roll journaled on the main frame on which the material is wound, means for rotating the roll including a variable speed transmission having a power shaft, a transmission shaft and a variable speed driving connection between said shafts, a motor for driving said power shaft, and means for changing the power transmission ratio of said variable speed transmission in accordance with changes of tension of the strip which causes a drag on the motor as the strip is being wound on said roll, said means including mechanism by which the drag in the motor is translated into a mechanical movement and this movement affects the transmission ratio of said variable speed transmission whereby the power delivered to the transmission shaft by the power shaft is varied in accordance with the drag on the motor to maintain an approximate constant tension of the strip at the said roll.

7. An apparatus for winding material in strip or wire form which is being delivered at a predetermined rate, said apparatus comprising a supporting frame, a winding drum for receiving the strip and mounted on said frame, an auxiliary frame, a motor on said auxiliary frame for rotating the drum, including a power shaft, said motor having a rockable stator which swings in proportion to the tension of said strip as the latter is being wound on said drum, a transmission shaft and a variable speed driving connection between said power shaft and transmission shaft, a pilot motor for adjusting said variable speed driving connection, and means responsive to the rocking of said stator for controlling the actuation of said pilot motor in accordance with the tension of the strip whereby a change of tension causes the pilot motor to change the speed ratio of said variable speed driving connection and thereby to change the speed of said drum in order to maintain an approximate constant tension on said strip.

8. An apparatus for winding strip or wire material onto a roll and delivered thereto at a predetermined rate, said apparatus including a variable speed transmission mechanism for rotating the roll at a rate dependent upon the tension of the strip, a motor for actuating said mechanism, said motor having a rockable stator which swings in proportion to the tension of said strip as the latter is being wound on said drum, and means responsive to the rocking of said stator for intermittently changing the power transmission ratio

of said mechanism in accordance with relatively small changes in the tension of said strip whereby the speed of the roll conforms closely to the tension of the wire.

9. An apparatus for winding strip or wire material onto a roll and delivered thereto at a predetermined rate, said apparatus including a variable speed transmission mechanism for rotating the roll at a rate dependent on the tension of the strip, a main motor for actuating said mechanism, said motor having a rockable stator which swings in proportion to the tension of said strip as the latter is being wound on said drum, and means responsive to the rocking of said stator and including a pilot motor for intermittently changing the speed transmission ratio of said mechanism inversely with the changes in the tension of the strip.

10. An apparatus for winding strip or wire material onto a roll and delivered thereto at a predetermined rate, said apparatus including a variable speed transmission mechanism for rotating the roll at a rate dependent on the tension of the strip, a main motor for actuating said mechanism, said motor having a rockable stator which swings in proportion to the tension of said strip as the latter is being wound on said drum, and means responsive to the rocking of said stator and including a pilot motor for intermittently changing the speed transmission ratio of said mechanism inversely with the changes in the tension of the strip, said pilot motor being controlled by the changes in load imposed on said main motor due to a change in tension in the strip as it is being wound on said roll.

11. An apparatus for winding strip or wire material onto a roll and delivered thereto at a constant rate, said apparatus including a variable speed transmission mechanism for rotating the roll at a speed dependent on the tension of the strip, a main motor for actuating said mechanism, means including a pilot motor for intermittently changing the power transmission ratio of said mechanism in accordance with relatively small changes in the tension of said strip, means operable by a change in load imposed on the main motor for energizing said pilot motor, said last mentioned means comprising a switch which is adapted to open and close contacts in response to changes of load imposed on said main motor, and means whereby the said electric switch makes and breaks the circuit to said pilot motor in order to control the operation of the pilot motor in accordance with the load imposed on said main motor.

12. An apparatus for winding strip or wire material onto a roll and delivered thereto at a predetermined rate, said apparatus including a variable speed transmission mechanism for rotating the roll at a rate dependent on the tension of the strip, a motor for actuating said mechanism, said motor having a rockable stator which swings in proportion to the tension of said strip as the latter is being wound on said roll, means for intermittently changing the transmission ratio of said mechanism in accordance with relatively small changes in the tension of said strip, and means responsive to the rocking of said stator for continuously changing the speed transmission ratio of said mechanism in accordance with relatively large changes in the tension of said strip whereby the speed of the roll conforms closely to the tension of the strip regardless of the amount of change in said tension.

13. An apparatus for winding material in strip

or wire form onto a roll and delivered thereto at a predetermined rate, said apparatus including a variable speed transmission mechanism for rotating the roll at a rate dependent on the rate of the strip material, a motor for actuating said mechanism, said motor having a rockable stator which swings in proportion to the tension of said strip as the latter is being wound on said roll, and means including a pilot motor and responsive to the rocking of said stator for intermittently changing the speed transmission ratio of said mechanism in accordance with relatively small changes in the tension of said strip, said transmission ratio changing means also including a periodic timing device which causes the intermittent energization of said pilot motor whereby the rotational speed of said roll is periodically changed to the proper speed to maintain the tension in said strip.

14. An apparatus for winding strip or wire material onto a roll and delivered thereto at a predetermined rate, said apparatus including a variable speed transmission mechanism for rotating the roll at a speed dependent on the tension of the strip, a motor for actuating said mechanism, said motor having a rockable stator which swings in proportion to the tension of said strip as the latter is being wound on said roll, means including a pilot motor and responsive to the rocking of said stator for changing the speed transmission ratio of said mechanism in accordance with changes in the tension of said strip, said transmission ratio changing means including a timing device for periodically energizing the pilot motor whereby the speed ratio of said transmission means is intermittently adjusted in response to a slight change in the tension in the strip from a predetermined amount, and means for automatically shunting said timing device when the changed tension exceeds said predetermined amount whereby the speed ratio of the power transmission means is continuously adjusted when the changed tension in said strip exceeds said predetermined amount.

15. An apparatus for winding strip or wire material onto a roll and delivered thereto at a predetermined rate, said apparatus including a variable speed transmission mechanism for rotating the roll at a rate dependent on the torque of a main motor having a stator and a rotor, said rotor being mechanically connected to said transmission mechanism, and means including a pilot motor for changing the speed transmission ratio of said mechanism in accordance with changes in the tension of said strip, said means also including a lever system connected at one end to said stator and at the other end to a shaft, said stator being adapted to be rocked through an angle dependent on the change of load imposed on the motor due to changed tension at said strip whereby the shaft is correspondingly rocked, contact members mounted on said shaft and adapted to be opened and closed depending on whether the shaft is rocked, and electrical circuit between said contact members and the pilot motor whereby when the stator of the main motor is rocked in accordance with the tension on said strip, the circuit is closed through said contacts to the pilot motor whereby an adjustment of the transmission ratio of said speed transmission mechanism is initiated and a change of speed is effected in the roll in order to maintain an approximate constant tension on the strip.

16. An apparatus for winding strip or wire material on a roll and delivered thereto at a pre-

determined rate, further apparatus including a variable speed transmission mechanism for rotating the roll at a rate dependent on the tension of the strip, a motor having a stator and a main rotor, said rotor being mechanically connected to said transmission mechanism, said stator being adapted to rotate with respect to said rotor, the amount of rotation being determined by the electrical reaction between the rotor and stator as the load on the motor is changed in response to a change in the tension at the strip and means including a pilot motor for changing the speed transmission ratio of said mechanism, said means also including a lever system connected at one end to said stator and at the other end to a shaft which is adapted to be rocked in any direction dependent on the direction in which the stator is rocked in response to changes in the tension of the strip, contact members operatively associated with said shaft, one of said contact members being adapted to be closed when the shaft is rocked in one direction and the other contact member being adapted to be closed when the shaft is rocked in the other direction, electrical circuits between each of said contact members and the pilot motor, said circuits being so arranged that upon closure of one contact member the pilot motor is caused to rotate in one direction and on closure of the other contact member the motor will rotate in the opposite direction, whereby when the stator is moved in accordance with change of tension on said strip, this movement is transmitted through the lever system and shaft to the contacts, which causes the pilot motor to move in any direction dependent on whether the tension on the strip is increased or decreased, whereby an adjustment in the proper direction is initiated to affect the power transmission ratio and to give the roll such a speed as will produce the normal tension in the strip material.

17. An apparatus for winding strip or wire material onto a roll and delivered thereto at an approximate constant rate, said apparatus including a variable speed transmission mechanism for rotating the roll at a rate dependent upon the tension of the strip, said mechanism being actuated by the rotor of a motor which also includes a stator, said stator being mounted on a frame through a rotary bearing and adapted to receive rotational energy from said rotor when the tension on the strip exceeds a predetermined

value, gravity-operating means for determining the tension of the strip at which the stator will be rotated, and means actuated by the rotary movement of the stator on its bearing for changing the power transmission ratio of said transmission mechanism whereby the speed of the roll is changed to maintain the tension at which the stator rotates.

18. A machine for operating upon strip or wire material and including a plurality of rolls, the material being unwound from one of the rolls of the machine and rewound on another roll of the machine, apparatus for driving one or more of said rolls at a rate dependent upon the tension 10 of the strip and including variable speed transmission mechanism, said mechanism being actuated by a motor, the stator of which is adapted to rotate through an angle dependent on any change of tension in the strip, and means actuated by the rotary movement of said stator for changing the power transmission ratio of said mechanism whereby the speed of the roll is controlled to maintain an approximately uniform tension on the strip.
19. An apparatus for winding strip or wire material onto a roll, the material being delivered thereto at an approximately constant rate of linear speed, said apparatus including a variable speed transmission mechanism for rotating the 20 roll at a rate dependent upon the tension of the strip, said mechanism being actuated by the rotor of a motor which also includes a stator, said stator being mounted on a frame through rotary bearings and adapted to receive increased or decreased rotational energy from said rotor when the tension of the strip changes from a predetermined amount, and adjustable means for predetermined the tension at which the stator will rotate, means including a contactor actuated by 30 the rotary movement of the stator on its bearings for changing the power transmission ratio of said transmission mechanism whereby the speed of the roll is changed to maintain approximately uniform tension on the strip, said contactor having means which operates in an anticipatory manner whereby under certain conditions the increased tension due to the increased roll diameter is anticipated and adjustments to compensate for this anticipatory increased tension.
